(57) **CLAIM**

The ornamental design for a canister, as shown and described.

DESCRIPTION

FIG. 1 is a perspective view of a large canister incorporating the design, shown in a closed position;

FIG. 2 is a right-side view of the large canister of FIG. 1;

FIG. 3 is a front view of the large canister of FIG. 1;

FIG. 4 is a bottom view of the large canister of FIG. 1;

FIG. 5 is a top view of the large canister of FIG. 1;

FIG. 6 is a perspective view of a medium canister incorporating the design, shown in a closed position;

FIG. 7 is a right-side view of the medium canister of FIG. 6;

FIG. 8 is a front view of the medium canister of FIG. 6;

FIG. 9 is a bottom view of the medium canister of FIG. 6;

FIG. 10 is a top view of the medium canister of FIG. 6;

FIG. 11 is a perspective view of a small canister incorporating the design, shown in a closed position;

FIG. 12 is a right-side view of the small canister of FIG. 11;

FIG. 13 is a front view of the small canister of FIG. 11;

FIG. 14 is a bottom view of the small canister of FIG. 11; and,

FIG. 15 is a top view of the small canister of FIG. 11.

A canister made in various sizes for storage of a variety of contents, allowing access to the contents thereof by removing the lid thereof.
